(57) **CLAIM**

The ornamental design for a lock escutcheon as shown and described.

DESCRIPTION

FIG. 1 is a perspective view of a first embodiment of the lock escutcheon, showing my new design;

FIG. 2 is a front elevational view of the lock escutcheon of FIG. 1;

FIG. 3 is a rear elevational view of the lock escutcheon of FIG. 1;

FIG. 4 is a left side elevational view of the lock escutcheon of FIG. 1;

FIG. 5 is a right side elevational view of the lock escutcheon of FIG. 1;

FIG. 6 is a top plan view of the lock escutcheon of FIG. 1;

FIG. 7 is a bottom plan view of the lock escutcheon of FIG. 1;

FIG. 8 is another perspective view of the lock escutcheon of FIG. 1;

FIG. 9 is another perspective view of the lock escutcheon of FIG. 1;

FIG. 10 is another perspective view of the lock escutcheon of FIG. 1;

FIG. 11 is a perspective view of a second embodiment of the lock escutcheon, showing my new design;

FIG. 12 is a front elevational view of the lock escutcheon of FIG. 11;

FIG. 13 is a rear elevational view of the lock escutcheon of FIG. 11;

FIG. 14 is a left side elevational view of the lock escutcheon of FIG. 11;

FIG. 15 is a right side elevational view of the lock escutcheon of FIG. 11;

FIG. 16 is a top plan view of the lock escutcheon of FIG. 11;

FIG. 17 is a bottom plan view of the lock escutcheon of FIG. 11;

FIG. 18 is another perspective view of the lock escutcheon of FIG. 11;

FIG. 19 is another perspective view of the lock escutcheon of FIG. 11; and,

FIG. 20 is another perspective view of the lock escutcheon of FIG. 11.

(Continued)

The broken line illustration of environmental structure in the drawings form no part of the claimed design.
